AUTOMATIC CIGARETTE-FEEDING DEVICES FOR CIGARETTE-PACKAGING MACHINES

Scipione Innocenti, Bologna, Italy

Application July 15, 1954, Serial No. 443,669

Claims priority, application Italy July 22, 1953

5 Claims. (Cl. 214—302)

This invention relates to cigarette-feeding devices for cigarette-packaging machines provided with a feed hopper and aims to provide a comparatively simple device which is reliable in operation and permits of automatically feeding to the feed hopper of the packaging machine the cigarettes contained in open-top boxes which have been filled at the cigarette-making machine and are automatically brought on to the feed hopper of the said cigarette-packaging machines and emptied thereunto.

According to the invention this end is attained by providing an open top and open sides holder for said open-top cigarette boxes which is mounted on a rockable arm adapted to shift said holder, while holding a cigarette box, from an upright position (which term includes also a slightly inclined position) in which the charging and discharging of a cigarette box therefrom takes place, into a capsized position, in which the cigarettes contained in the box are dropped into the feed hopper of the cigarette-packaging machine.

Further objects of the invention are to provide means for automatically stepwise feeding said open-top cigarette boxes in upright position until they come to be in line with said box holder in its upright position and then inserting the aligned cigarette box into the holder, while pushing thereout an empty box still contained therein after a preceding emptying, means being also provided for carrying away said empty boxes after their expulsion from said holder.

Other objects and features of the invention will appear from the following specification.

With reference to the attached drawings:

Fig. 1 is a diagrammatic plan view of a cigarette-feeding device annexed to a cigarette-packaging machine.

Fig. 2 is a vertical section on line II—II of Fig. 1.

Fig. 3 is an elevation of the machine, viewed in the direction of arrows III—III of Figure 1.

Fig. 4 is a section on line IV—IV of Fig. 1.

Figs. 5 and 6 are sections through a cigarette box holder which is shown respectively in its upright and its capsized position.

Figs. 7 and 8 are external side views of the box holder and annexed parts in positions corresponding to those shown in Figures 5 and 6, respectively.

Fig. 9 is a plan view, with parts in section, of the box holder shown in Figure 8.

Fig. 10 shows the control cam of the main parts of the device.

Figs. 11 and 12 show the device for inserting the full cigarette boxes into the holder and for discharging the empty boxes thereout, and

Fig. 13 shows in side elevation another embodiment of a device for stepwise feeding the cigarette boxes to the position in line with the upright holder.

With reference to the figures, 1 is a part of an automatic cigarette-packaging machine provided with a vertical feed hopper 2. The cigarettes S delivered from the cigarette-making machine are contained in collecting boxes C

2

which are opened at their top and at one of their front sides (Figures 2 and 5).

In order to feed the cigarettes to be packaged into the feed hopper 2, the machine is provided with a rockable cigarette box holder 3 which capsizes one-by-one the boxes C filled with cigarettes onto said feed hopper 2 and then returns same in upright position. Said holder 3 is in the form of a casing which is open at its top and at its side walls through which a cigarette-collecting box 4 may be slid. Holder 3 is fastened to the end of arms 5 rockably mounted on to a horizontal shaft 5 journaled in a part 6 of the machine frame. The weight of arms 4 and holder 3 are balanced by a counterweight 7. A motor and drive unit 8 imparts to shaft 5 such a rocking motion as to rock holder 3 alternatively to two end positions (Figure 4), viz. an upright position on the rear part of the packaging machine 1 (cigarette box-inserting and discharging position, Figures 1, 2, 3, 5 and 7) and an upset or capsized position (cigarette box-emptying position, Figures 6 and 8). In its upright position the holder 3 bears with its bottom on a cross piece 9, forming part of the machine frame and provided with rollers 10 which project in part into holder 3 through openings in its bottom (Fig. 5), while in its upset position holder 3 bears with its open top edge on the mouth of feed hopper 2.

In the embodiment as shown, the essential parts of the feeding device are controlled by a single cam 11 which is continuously rotated by motor and drive unit 8 and is provided with an annular cam groove in which a roller 112 is engaged, carried by a rocking lever 12 fulcrumed at 212 to a pivot carried by the machine frame. One arm of said lever 12 is operatively connected through levers 13, 14, 15 and 16 with the control shaft 5 of box holder 3 (Figs. 1, 3 and 10) in such a manner as to be rocked thereby.

Holder 3 is provided at its interior with box-spacing and centering members 17 and with slightly projecting parts 117 by its mouth, which prevent of the boxes C dropping out of holder 3 by its capsizing.

Furthermore, in proximity of the open top of holder 3 a pair of opposite cigarette-holding plates 18 are fitted on small parallel shafts 19 journaled to and projecting with one end out of said holder 3. To each of the projecting ends of shafts 19 an arm 20 is fitted, whereby the arm ends are connected together by tension springs 21. To the end of said arms 20 abutment rollers 22 are fitted so as to coact with cam surfaces 24 fitted on the machine frame, when the holder 3 is rocked to its upright position and to coact with abutment members 26 provided on hopper 2, when the said holder 3 is rocked to capsized position. When the holder is near this end position, arms 20 are swung with their spring anchoring ends over their shaft axes or centres and thus snap on either side of the plane passing through said axes, into the positions shown in Figures 7 and 8, whereby the cigarette-holding plates 18 are fastened at such an angle on shafts 19, with respect to arms 20 as to be swung into horizontal or cigarette-holding position (Figs. 5 and 7) when the holder is in its upright position and to be swung into vertical or open position when the holder 3 is capsized (Figs. 6 and 8).

The insertion of the cigarette boxes C into the holder 3 and the consequent pushing of the empty boxes thereout are mechanically effected by means of two automatic charging and discharging devices fitted on opposite sides of the upright holder 3.

The charging device comprises a pair of parallel substantially horizontal chains 27 fitted at one side of holder 3, perpendicularly to its rocking shaft 5 and tensioned between two gear pairs 28 which are driven stepwise

towards the casing 3 by means of a pair of ratchet wheels 29 which are rotated by pawls 129 whose movement is controlled by a pair of levers 30 hinged to rocking lever 12. Chains 27 are connected by cross bars 31 formed in such a manner as to each hold a cigarette box C. The movement of the chains 27 is so timed with regards to the rocking of box holder 3, that at each return of this latter in its upright position, a box C on cross bar 9 comes to be in line with said holder 3.

A transversal chain 32 tensioned between pinions 34 is provided with a finger 33 which engages the boxes as soon as same are brought adjacent to the holder 3 and pushes same sidewise thereinto. This sidewise charging movement of the boxes C is eased by the provision of rollers 10 (Figures 1, 2 and 5) upon which the boxes run. Each full box C, by being pushed into the holder 3 pushes in its turn the empty box out of the same holder 3.

The device for discharging the empty boxes C, after same have been pushed out of holder 3, comprises a carriage 35 running on substantially horizontal rails 36 (Figures 1, 2, 4 and 12) in a direction at right angles to the axis of shaft 5, viz. parallel to box-feeding chains 27 and arranged on the opposite side of holder 3. Carriage 35 is reciprocated by means of levers 37 and 41 (Figures 4 and 12) which are operatively connected for example with the rocking lever 12. Thus when an empty box is pushed out of holder 3, it is slid onto carriage 35 which subsequently by running on rails 36 away from holder 3, pushes the empty box carried thereby beyond abutment members 42 provided on the machine frame (Figures 1 and 12) and which yields when engaged by a box carried by the carriage 35 while moving away from the upright holder position, but are held back by the same abutment members 42 by the successive return movement of the said carriage which returns empty to its starting position, ready to take up and carry away another empty box expelled out of holder 3.

According to another embodiment of box-charging device as shown in Figure 13, the device comprises a carriage 43 provided with a rack 143 and rolling on rails 44, and which is provided at its upper part with a number of clips 45 between which are inserted the cigarette boxes C. The rails are inclined towards the charging position of the usual rocking holder 3 (not shown), at the side of which the rails are fitted, and is advanced stepwise towards the said holder 3 either by gravity or by the action of suitable means (springs, counterweights) under the control of an escapement pawl 46 co-acting with said rack 143 and which is driven against the action of a spring 47 by rocking levers 48 and 49. The boxes are charged into the holder as described, by means of abutment members 33 carried by chain 32. When the carriage reaches the end of its downward path (no more full boxes thereon) it is pulled upwardly to its starting position by means of handle 50 and is again loaded with cigarette boxes C.

From the foregoing it is apparent that a device has been provided by means of which the cigarettes are fed automatically into the hopper of a cigarette-packaging machine. The operation of the whole device may be summarized as follows, reference being had to Figures 1 and 2, and 13:

The cigarettes to be fed are contained in open-top rectangular boxes C which are fitted (by hand) on feed means (chains 28 in Fig. 1 or carriage 43 in Fig. 13) which are driven stepwise towards an end position, in which they come to be in line with a box holder 3 in upright position, as will be better explained hereinafter. Parallel to these feed means and spaced therefrom are rails 36 along one end portion of which a discharge carriage 35 may be reciprocated by a short distance, which substantially corresponds to the length of the small sides of the cigarette boxes. Between these feed and discharge means the said cigarette box holder 3 is mounted on arms fitted on a rocking shaft 5 and which is rocked

from said upright, or box-charging and discharging position (Fig. 1) to box-emptying position (Figs. 5 and 6) in which the box holder 3 is capsized on the conventional feed hopper 2 of the cigarette-packaging machine. When the holder is in upright position, a finger 43 (or other abutment means) carried by a positively driven endless chain 32 pushes (or by a member reciprocated in timed relation with the other machine parts) sidewise a cigarette box C into the holder 3, thus expelling onto the carriage 35 the empty box still contained in the holder 3. When the holder 3 has received a full cigarette box, it is rocked to said capsized position, in which the cigarettes are allowed to drop into the feed hopper 2 of the packaging machine.

15 All these operations, viz. (a) rocking of the box holder; (b) charging and discharging the boxes into and from said holder and (c) operating cigarette holding means and (d) bringing the full boxes in line with the upright holder and shifting the discharged empty boxes towards their discharge position are controlled in timed relation by cam 11.

From the foregoing it is apparent that the device according to the invention may undergo numerous changes without departing from the basic principle of the invention. Thus for example the discharging device comprising the carriage 35 and annexed parts could be replaced by a simple chute or by an endless belt conveyor adapted to discharge the empty boxes into a suitable container; the box-shifting finger-carrying chain 32 could be driven, in timed relation to the other parts, either by the driving means of the cam or by a separate motor and step-down drive; this same shifting device could be replaced by a reciprocating member driven by cam 11, and other equivalent arrangement, as will be apparent to those skilled in the art.

I claim:

1. In an automatic feeding device for cigarette-packaging machines provided with a vertical feed hopper and to which the cigarettes are fed from open-top boxes; a shaft arranged in parallel relation to the mouth of said hopper; an arm fastened to said shaft; a cigarette box holder, open at its top and sides, fastened to said arm; means for rocking said shaft so as to bring said box holder from a substantially upright box-receiving position to a position in which said box holder and box therein are capsized on the said feed hopper; means for bringing full boxes in line with one side of said box holder; means for receiving empty boxes in line with the opposite side of said box holder; means for pushing the full boxes having reached the position in line with the box holder thereinto, while expelling thereout the empty box which was held therein and means for discharging the said empty boxes, in which the feeding of the cigarette boxes into said holder is accomplished by a conveyor on which said boxes are arranged vertically, means for stepwise shifting said conveyor and continuously driven endless means fitted on a pair of wheels and carrying at least a projecting finger in such a position as to push sidewise the cigarette box which is aligned with said box holder from one side into said holder while expelling from the opposite holder side the empty box contained therein.

2. In an automatic feeding device for cigarette-packaging machines provided with a vertical feed hopper and to which the cigarettes are fed from open-top boxes; a shaft arranged in parallel relation to the mouth of said hopper; an arm fastened to said shaft; a cigarette box holder, open at its top and sides, fastened to said arm; means for rocking said shaft so as to bring said box holder from a substantially upright box-receiving position to a position in which said box holder and box therein are capsized on the said feed hopper; means for bringing full boxes in line with one side of said box holder; means for receiving empty boxes in line with the opposite side of said box holder; means for pushing the full boxes having reached the position in line with the

box holder thereinto, while expelling thereout the empty box which was held therein and means for discharging the said empty boxes, in which the feeding of the cigarette boxes into said holder is accomplished by a pair of substantially horizontal rails, a carriage provided with a rack part adapted to run on said carriage; cigarette box-holding means on said carriage; positively driven pawl means engaging said rack part of said carriage and shifting same stepwise towards the upright cigarette holder position and continuously driven endless means fitted on a pair of wheels and carrying at least a projecting finger in such a position as to engage sidewise the cigarette box held by said cigarette box-holding means on said carriage in the position in line with said rockable cigarette box holder and to push said box from one side into said cigarette box holder while expelling from the opposite holder side the empty box contained therein.

3. In an automatic feeding device for cigarette-packaging machines provided with a vertical feed hopper and to which the cigarettes are fed from open-top boxes; a shaft arranged in parallel relation to the mouth of said hopper; an arm fastened to said shaft; a cigarette box holder, open at its top and sides, fastened to said arm; means for rocking said shaft so as to bring said box holder from a substantially upright box-receiving position to a position in which said box holder and box therein are capsized on the said feed hopper; means for bringing full boxes in line with one side of said box holder; means for receiving empty boxes in line with the opposite side of said box holder; means for pushing the full boxes having reached the position in line with the box holder thereinto, while expelling thereout the empty box which was held therein and means for discharging the said empty boxes, in which the means for discharging the said empty boxes comprises at the expelling side of said cigarette box holder a carriage mounted on rails; means for shifting said carriage from an empty box-taking position, in line with said box holder, while same is in charging or upright position, towards the cigarette box discharging position, so as to leave the space in line with said box holder free; yielding abutment means acting so as to permit the empty boxes on said carriage being shifted towards their discharging position, but not in reverse direction and means for returning the said carriage to charging position while leaving the empty box which was laden thereon beyond said yielding abutment means.

4. An automatic feeding device for cigarette-packaging machines provided with a frame and a substantially

vertical feed hopper to which the cigarettes are discharged from open-top boxes and comprising a cigarette box holder mounted on arms fastened to a horizontal shaft and having an open top and open sides, means for 5 rocking said shaft so as to cause said arms to be swung along vertical planes and to bring said holder from an upright, cigarette box-charging and discharging position to a capsized, cigarette-dropping position on said feed hopper; spring-urged means on said box holder coacting with a part of said frame in proximity to the upright holder position, for substantially closing the top of said holder when the same is in upright position; means on said feed hopper coacting with said spring-urged means on the box holder for opening the top of said box holder in proximity to its capsized position; box-supporting means advancing stepwise along substantially horizontal paths parallel to said vertical arms-rocking planes for bringing said boxes, successively, in line with one of the open sides of the box holder while in upright position; 10 means advancing in a directions at right angles to said box-supporting means and having means projecting in the path of the last box on said supporting means for shifting said box into the said box holder, which at that time is in line therewith, while expelling from the opposite holder side the box which has been emptied by the preceding capsizing of the said holder; and means for carrying away said expelled empty box.

5. An automatic feeding device according to claim 4, in which the means for controlling the movements of 15 swinging of said box-holding arms in timed relation with the other box advancing means comprises a motor-driven cam provided with an annular cam groove; a rocking lever provided with a roller engaged by said annular cam groove; lever means operatively connecting said rocking lever with said box holder rocking shaft for alternatively 20 rocking said box holder from said upright to said capsized position; and lever and pawl means operatively connected to said rocking lever for engaging said cigarette box-advancing means and causing the same to advance 25 stepwise towards the position in line with a side of the box holder in its upright position.
